F. A. KOLB

THEFTPROOF DEVICE FOR WATT HOUR METERS

Filed May 23, 1924

UNITED STATES PATENT OFFICE.

FRANK A. KOLB, OF HAMMOND, INDIANA, ASSIGNOR OF ONE-HALF TO MORSE
DELLPLAIN, OF HAMMOND, INDIANA.

THEFTPROOF DEVICE FOR WATT HOUR METERS.

Application filed May 23, 1924. Serial No. 715,398.

To all whom it may concern:

Be it known that I, FRANK A. KOLB, a citizen of the United States, and a resident of Hammond, county of Lake, and State of Indiana, have invented certain new and useful Improvements in a Theftproof Device for Watt Hour Meters, of which the following is a specification.

My invention pertains to a theft-proof device for watthour meters, and the object of this invention is to provide means for preventing the theft of electric current in installations using watthour meters; and another object is to provide means in connection with a watthour meter, so arranged that any attempt to insert a wire from the line terminal to the load terminal of the watthour meter will cause a short circuit, thereby blowing the line fuse.

With the use of a watthour meter theft of current is frequently resorted to and is usually accomplished by inserting one end of a wire in the line terminal of a watthouse meter and the other end of a wire in the load terminal, thereby shunting the current coil of the meter and allowing the use of unmetered current. I prevent such theft with my invention, by replacing the bushing and terminal which is connected to the load side of the current coil of the meter, with a special bushing and terminal, and connecting this terminal electrically to a point which will give a part of said special terminal an electrical potential which is the opposite to the electrical potential of the main part of said terminal.

Other objects will appear hereinafter.

The invention consists in the combinations and arrangements of parts hereinafter described and claimed.

The invention will be best understood by reference to the accompanying drawings forming a part of this specification, and in which—

Fig. 1 is a partial elevational view of a watthour meter with my invention mounted in position thereon;

Fig. 2 is a detail view of the terminal assembly;

Fig. 3 is a plan view of my invention;

Fig. 4 is a vertical sectional view taken on line 4-4 of Fig. 3;

Fig. 5 is a horizontal sectional view taken on line 5-5 of Fig. 4; and

Fig. 6 is a cross sectional view taken on line 6-6 of Fig. 4.

In the drawings I have shown an embodiment of my invention applied to a watt-hour meter which includes the glass disk 10 and the terminal box 11 with its terminal chamber 11'. In this chamber 11' of the terminal box I mount my improved device D, by replacing a bushing and terminal on the load side of the meter, and connecting my device with the load wire 12 and with the line side of the current coil of the meter; and other load terminal and bushing 13 with its connected load wire 14, and the line terminals and bushings 15 and 16 with the connected negative and positive line wires 17 and 18, being retained, as indicated in Fig. 1.

My improved device comprises a main insulating bushing 20 with a channel extending therethrough which is smaller at its lower end 21, to form a shoulder 22, upon which is seated a metal ring 23, preferably of copper, and a main terminal 24 is mounted above said ring and insulated therefrom by a fiber washer 25. A chamber 26 is provided in said terminal 24 and a screw 27 extends through the walls of said main bushing and said terminal to press and retain the exposed metal end 12' of load wire 12 against the inner terminal wall in chamber 26, said wire being exposed only at its end and the insulation being retained around said wire extending through ring 23 and through the restricted opening 21. Said terminal 24 is preferably flattened at opposite sides 24' to readily assume the correct position in its bushing 20. Said main terminal has an upper lug 28 with a terminal screw 29 and a washer 30 for connecting said terminal in the usual manner to the load side of the current coil (not shown) of the meter.

Means is provided for electrically connecting a part of my improved terminal device, as a copper ring 23, to a point which has a potential opposite to the potential of said terminal device, and preferably to a point on the line side of said meter, which will give said part or ring a potential opposite

to the potential of the main part of said terminal device. This means preferably comprises a terminal assembly including a metal sleeve 30 carrying a metal stem 31 which is 5 threaded into an opening in ring 23, while an insulating bushing 32 surrounds said sleeve and is mounted in the main bushing 20. An insulated copper bar 33 has its exposed end 33' fastened in said sleeve by a binding 10 screw 34 threaded in the sleeve, and has its opposite end electrically connected with the negative line terminal 15, as by means of a binding screw 35. The device is so placed in the meter that both connections of bar 33 are within the terminal box 11, and thus out 15 of reach and out of view when said box is closed.

In equipping an installed meter with my device, or in installing a meter equipped with 20 my device, the insulation of the load wire is removed only far enough from the end of the wire to make contact with the new terminal 24. This allows the insulation on the load wire to extend through the ring and 25 prevent contact between the ring and the load wire, and the ring is made of such a diameter that it merely permits the insertion of a shunt wire between said ring and said load wire, and only by making contact between the inserted shunt wire and the ring, thus making it impossible to make an additional electrical contact with the terminal 24, without first making contact with the ring 28.

35 With this mechanical arrangement of the parts, any attempt to insert an electrical conductor, extending from the line terminal to the load terminal will result in a short circuit, thereby blowing the line fuse. If an 40 electrical conductor is inserted in the load terminal, so as to contact with the actual terminal or main terminal 24, a short circuit will result between the copper ring and said actual terminal. And this device can 45 either be incorporated in the manufacture of watthour meters, or it can be inserted in existing meters by replacing one of the load terminals with my improved device and attaching the device electrically to the line 50 terminal of opposite potential, as shown in Fig. 1.

While I have illustrated and described the preferred form of construction for carrying 55 my invention into effect, this is capable of variation and modification without departing from the spirit of the invention. I, therefore, do not wish to be limited to the precise details of construction set forth, but desire to avail myself of such variations and 60 modifications as come within the scope of the appended claims.

Having described my invention, what I claim as new and desire to secure by Letters Patent is:

65 1. In an electric meter, a device of the

character described comprising a bushing with terminal members therein insulated from each other, and means for connecting one of said members to a point in said meter of different potential than the other of said 70 terminal members, to prevent theft of current from said meter.

2. In an electric meter, a device comprising 75 a bushing with terminal means therein, a part of said terminal means in said bushing being insulated from the main terminal portion, means for connecting said part to a point in said meter which will give said part the opposite electrical potential from the main terminal portion and will prevent 80 shunting of the current coil of the meter.

3. In an electric meter, a device of the character described comprising a main terminal with a bushing, metallic means in said bushing and insulated from said main terminal, and electricity conducting means connecting said metallic means with a point of opposite potential to the main terminal to cause a short circuit when a wire is inserted 85 in said bushing and thereby to prevent 90 shunting of the current coil of the meter.

4. In an electric meter including terminals, a terminal device constituting one of 95 said terminals and comprising a bushing, a main terminal mounted therein and connectible with the load side of the current coil, metallic means mounted in said bushing and insulated from said main terminal, and means electrically connected with a line terminal of opposite potential from said main 100 terminal, said metallic means and entire device being arranged to prevent connecting said terminals by a shunt wire and to prevent the theft of current.

5. In an electrical meter, a terminal box 105 with line terminals and load terminals and terminal wires connected thereto, one of said terminals comprising a bushing, a main terminal member mounted in said bushing, a metallic member mounted in said bushing 110 and insulated from said main terminal member, an insulated terminal wire extending from said main terminal member through said bushing and being only slightly spaced from said metallic member to cause a shunt 115 wire to engage said metallic member when inserted in said bushing, and electricity conducting means in said terminal box extending from said metallic member through said bushing and joined to another of said terminals to prevent theft of current from said 120 meter.

6. In a watthour meter, a device comprising a terminal with a bushing, a metal ring in said bushing and insulated from said terminal, a terminal wire extending from said terminal through said ring and being insulated therefrom, said ring being slightly larger than said insulated wire to engage a shunt wire that may be inserted between said 125 130

insulated wire and said ring, and electricity conducting means extending from said ring to a point of opposite potential from said terminal.

- 5 7. In a watthour meter, a device comprising a main terminal with a bushing, a metal member in said bushing and insulated from said terminal, an auxiliary terminal removably mounted on said member and extending 10 from said bushing, and current conducting means connecting said auxiliary terminal with a point of opposite potential from said main terminal.

- 15 8. In a watthour meter, a main terminal with a bushing, a metallic member in said bushing and insulated from said terminal, metallic means mounted on said member and extending from said bushing, and a metal bar detachably connected to said metallic 20 means and to a point of opposite potential from said main terminal.

- 25 9. In a watthour meter, a terminal with a bushing, a metal member in said bushing and insulated from said terminal, a sleeve with a binding screw mounted on said member, and electricity conducting means removably connected to said sleeve with said binding screw and to a terminal of opposite potential than the first terminal.

- 30 10. In a watthour meter, a device comprising a main terminal housed in a bushing, a metal ring supported in said bushing and separated from said terminal by an insulating gasket, a binding screw extending in 35 said terminal for holding a terminal wire extending through said ring and said gasket, an auxiliary bushing mounted in said first bushing, an auxiliary terminal mounted in said auxiliary bushing, said auxiliary terminal being removably fastened to said ring and containing a binding screw, and a metal 40 bar held by the last said binding screw and attached to a point in said meter for impart-

ing to said auxiliary terminal and said ring a potential different from the potential of 45 said main terminal.

11. In a watthour meter having a terminal box with terminals therein, one of said terminals comprising a bushing, a main terminal mounted in said bushing, a metal ring 50 mounted in said bushing and insulated from said main terminal, a terminal wire extending through said ring and connected in said main terminal, said ring being but slightly larger than said terminal wire to engage 55 a shunt wire when inserted between it and said terminal wire, an auxiliary terminal connected to said ring, and an electric conductor extending from said auxiliary terminal to a terminal of opposite potential 60 from said main terminal.

12. In a watthour meter having a terminal box with line terminals and load terminals housed therein, one of the load terminals comprising a bushing, a main terminal 65 mounted therein and having a part extending therefrom for connection to the load side of the current coil of said meter, a metal ring mounted in said bushing, insulating means placed between said main terminal 70 and ring, a binding screw extending into said main terminal for holding a terminal wire extending with insulation through said ring, said ring providing a small space between its interior and said insulated terminal 75 wire, an auxiliary terminal connected to said ring, an auxiliary bushing surrounding said auxiliary terminal, and an insulated bar extending from said auxiliary terminal to a line terminal, for imparting to said auxiliary terminal and ring a potential different 80 from that of said main terminal.

In testimony whereof I have signed my name to this specification.

FRANK A. KOLB.
